William H. Spake

Cadrow & Co.

UNITED STATES PATENT OFFICE.

JOHN STAPLES AND WILLIAM H. SPAKE, OF ENNIS, TEXAS.

FIRE-ALARM.

SPECIFICATION forming part of Letters Patent No. 592,643, dated October 26, 1897.

Application filed December 5, 1896. Serial No. 614,636. (No model.)

To all whom it may concern:

Be it known that we, JOHN STAPLES and WILLIAM H. SPAKE, citizens of the United States, residing at Ennis, in the county of 5 Ellis and State of Texas, have invented a new and useful Automatic Fire-Alarm, of which the following is a specification.

This invention relates to automatic fire alarms; and it has for its object to provide 10 an improved alarm of this character especially designed for use in hotels and other large buildings having a large number of rooms.

To this end the invention contemplates an 15 alarm apparatus having simple and efficient means for causing an alarm to be automatically sounded when a fire has started in a building and at the same time to annunciate or indicate the particular room or portion of 20 the building where the fire is located.

With these and other objects in view, which 25 will readily appear as the nature of the invention is better understood, the same consists in the novel construction, combination, and arrangement of parts hereinafter more 30 fully described, illustrated, and claimed.

In the drawings, Figure 1 is a front elevation of an automatic fire alarm and indicating 35 apparatus constructed in accordance with the 30 present invention and showing the various parts of the mechanism in their set positions. Fig. 2 is a similar view showing the alarm in operation for indicating a fire in certain parts or rooms of a building. Fig. 3 is a transverse 40 sectional view on the line 3-3 of Fig. 1. Fig. 4 is a detail sectional view on the line 4-4 of Fig. 3.

Referring to the accompanying drawings, the numeral 1 designates an indicator casing 40 or box adapted to be secured on a wall or other convenient place and provided in the top and bottom with a plurality of rod-openings 2, the casing 1 being preferably inclosed at its front side by a removable front board 45 or door 3, which is shown removed in Figs. 1 and 2 of the drawings, so as to expose the interior working parts of the apparatus. The rod-openings 2 in the top and bottom of the casing 1 are arranged in regular order and in 50 vertical alinement, so as to accommodate for movement therein the indicator-rods 4, extending above and below the casing and carry-

ing at their lower ends below the bottom of the casing the indicator plates or cards 5, on which plates or cards are placed the numbers 55 of the rooms in the building in which the apparatus is located, it being understood that each indicator-rod represents one particular room or part of a building, so that when one of the indicator-rods 4 is drawn downward, so as to 60 display the number on the plate or card carried thereby, it can be readily seen at a glance what particular room or part of a building is on fire.

The indicator-casing 1 is made sufficiently 65 large to accommodate the requisite number of indicator-rods 4, according to the number of rooms or parts of the building included in the circuit of the apparatus, and for the purpose of best carrying out the present invention the 70 indicator-rods 4 are arranged in separate rows from end to end of the casing, so that a single flexible trip connection or cord 6 can be used with all of the indicator-rods 4 in one row, as will be more fully explained in connection 75 with the operation of these rods. The said indicator-rods 4 are provided with looped upper ends 7, extending through the openings 2 in the top of the casing 1, and these looped upper ends 7 of the indicator-rods have connected therewith one end of the light connecting-wires 8, which wires are suitably guided from the indicator-casing to the rooms or parts of the building which are provided with the ordinary fusible fire cords or ropes 9, which 80 fire ropes or cords 9 have a connection with the connecting-wires 8, it of course being understood that each indicator-rod 4 has a separate wire and cord connection 8 and 9 therewith, so as to be operated independently of the other 90 rods. The fusible fire-cords 9 are strung on the ceilings and walls of the rooms of the building in the usual manner, so as to be exposed to fire, which will readily burn the cords 9 and immediately slacken the connections 95 therewith, so as to cause an alarm to be automatically sounded through the medium of the mechanism forming a part of this invention.

The looped upper ends 7 of the indicator-rods 4 receive therein horizontal stop-rods 10, 100 secured on top of the casing 1, for the purpose of limiting the downward movement of the rods, and said rods 4 are provided within the casing 1 and at points intermediate of their

ends with offstanding depressing-hooks 11, disposed above and adapted to engage with the flexible trip connections or cords 6. The rods 4 are drawn in a downward direction to 5 carry their hooks 11 against the flexible trip connections or cords 6 by means of the retractile springs 12, secured fast at their lower ends, as at 13, to the bottom of the casing 1 and connected at their upper ends, as at 14, with the 10 rods 4, preferably at the point where the hooks 11 are projected laterally from such rods. The springs 12 loosely encircle the rods 4 to provide for normally exerting a downward pull thereon, so that when released from their 15 connections 8 and 9 the hooks 11 will cause to be depressed the trip connections or cords 6 and cause an alarm to be sounded.

As already referred to, a single flexible trip connection or cord 6 is employed with 20 each row of indicator-rods 4, and the said trip-cord 6 is arranged within the upper part of the casing 1 and secured fast at one end, as at 15, to one end of the casing. The opposite end of the trip-cord 6 is connected to the 25 cross-bar 16 of an inverted-U-shaped trip-bail 17, pivotally mounted in suitable bearings 18 at one end of the casing 1 within the latter and provided at one of its terminals with an offstanding rock-arm 19, adapted to 30 work opposite and against a spring-projected push-button 20 of an ordinary spring alarm-bell 21, preferably mounted on the exterior of the casing at one end thereof. The said spring-projected push-button 20 is provided 35 with a check-collar 22, which normally is disposed in the path of the clapper-arm 23 of the bell, so that when the button 20 is forced inward by the arm 19 the clapper-arm of the bell will be released and free to operate, so 40 as to ring the bell and sound an alarm. A spring-arm 24 is secured fast at one end, as at 25, to one end of the casing and normally bears against the inner side of the rock-arm 19 to hold such arm normally out of engagement 45 with the push-button 20 of the bell. By reason of forming the bail 17 in the shape described all of the trip connections or cords 6 within the casing may be connected thereto, as illustrated in Fig. 3 of the drawings.

50 The connecting-wires 8 are guided throughout the building around glass or other suitable pulleys or in any other convenient manner, but these connecting-wires and the fire cords or ropes 9 are drawn taut, so as to provide for holding the indicator-rods 4 elevated and thereby expand or extend the springs 12 connected therewith. With the parts thus set it will be obvious that a burning out of one of the fire-cords will permit the spring 12 55 for the indicator-rod having a connection with such cord to retract and sharply draw the indicator-rod downward, exposing the indicator plate or card 5 and drawing the hook 11 of the rod against the trip-cord 6. The 60 depression of the cord 6 by the hook 11 of the retracted indicator-rod will swing the bail 17

in a direction to carry the rock-arm thereof against the push-button of the bell, so as to cause such bell to sound an alarm.

The many advantages of the herein-described fire alarm and indicating apparatus will readily appear to those skilled in the art, and it will be understood that various changes in the form, proportion, and the minor details of construction may be resorted to without departing from the principle or sacrificing any of the advantages of this invention.

Having thus described the invention, what is claimed, and desired to be secured by Letters Patent, is—

1. In an automatic fire alarm and indicator, the casing, a plurality of spring-retracted indicator-rods mounted vertically within the casing and carrying at their lower ends below the latter indicating plates or cards, said indicator-rods being provided with upper looped ends extending through openings formed in the top of the casing, and also formed with intermediate laterally-disposed depressing-hooks, horizontal stop-rods secured on top of the casing and extending through the looped upper ends of said indicator-rods to limit the downward movement thereof, suitably-arranged fire-cords having connections with the upper looped ends of 95 said indicator-rods, an alarm-bell, trip mechanism for the bell having a pivotal bail, and a trip-cord for each row of indicator-rods, each trip-cord being connected at one end with said bail and at its other end to an oppositely-located point of attachment within the casing, substantially as set forth.

2. In an automatic fire alarm and indicator, the casing, a plurality of spring-retracted indicator-rods mounted vertically within the 105 casing and carrying at their lower ends indicating plates or cards, said indicator-rods being provided intermediate of their ends within the casing with lateral depressing-hooks, fire-cords having connections with the 110 upper ends of said indicator-rods, an alarm-bell mounted at one end of the casing and having a spring-projected push-button extended into the casing, a spring-adjusted trip-bail pivotally mounted within the casing 115 at one end thereof and provided at one of its terminals with an offstanding rock-arm working opposite and against said push-button, and a trip-cord arranged under the lateral hooks of each row of indicator-rods, each 120 trip-cord being connected at one end with said trip mechanism and at its other end to a fixed point of attachment within the casing, substantially as set forth.

In testimony that we claim the foregoing as 125 our own we have hereto affixed our signatures in the presence of two witnesses.

JOHN STAPLES.

WILLIAM H. SPAKE.
